ROOFING RETAINER

Homer C. Young, Milwaukee, Wis.

Application January 21, 1949, Serial No. 71,993

4 Claims. (Cl. 108—33)

1

The present invention relates to roofing and the like and more particularly to retaining or fastening means for roofing sections or shingles.

An object of the invention is to provide an improved roofing retainer for preventing lifting and tearing of roofing sections or shingles by wind action, and which can be easily, quickly, and securely applied to both old and new roofs.

Another object is to provide a roofing retainer of this character which is adapted for insertion in shingle slots and which will avoid interference with roofing nails.

Still another object is to provide a roofing retainer which can be firmly anchored in place without hammering or otherwise injuring the weather surface of the roofing.

A further object is to provide a roofing retainer of simple and durable construction which is capable of inexpensive manufacture.

A still further object is to perfect details of construction generally.

The invention further consists in the several features hereinafter described and claimed.

In the accompanying drawing, illustrating certain embodiments of the invention,

Fig. 1 is a fragmentary top view of a roof provided with retainers of the invention;

Fig. 2 is an enlarged fragmentary top view of the roof with a retainer in applied position;

Fig. 3 is a fragmentary sectional elevational view of the roof, taken generally on the line 3—3 of Fig. 1;

Fig. 4 is a perspective view of a shingle retainer;

Fig. 5 is a side view of the retainer;

Fig. 6 is a view of a multiple retainer blank;

Fig. 7 is a side view of a modified form of shingle retainer;

Fig. 8 is a sectional view of the roof taken generally on the line 8—8 of Fig. 1, showing another form of retainer for use at an edge of the roof, and

Fig. 9 is a perspective view of the retainer of Fig. 8.

In the drawing, 15 designates a board roof on which successive overlapping courses of roofing sections 16, here shown to be shingle strips, are secured by nails 17 in the usual manner, the shingle strips being formed of the usual asphaltic composition and having the usual mineral surfacing 18. Each shingle strip has parallel slots 19 extending upwardly from its lower edge to divide the strip into rectangular shingle portions or tabs 20, and the ends of the aligned shingle strips are notched to form similar slots. The nails 17 are driven through the shingle strips near and above the upper ends of the slots 19. The lower edges of the shingle strips in the successive courses are disposed approximately at the upper ends of the slots in the immediately underlying strips, and the shingle portions or tabs 20 are approximately centered with respect

2

to the slots of the underlying strips. In roofing of this type, strong wind action has a tendency to lift the shingle tabs and to cause weakening, tearing and failure of the roofing.

5 The roofing retainer or clip shown in details in Figs. 2 to 6 is designated generally by the numeral 21 and comprises a piece of weather-resistant resilient sheet metal bent to form a substantially flat rectangular base plate 22 and an outwardly offset spring tongue 23 projecting upwardly from the middle of the upper edge portion of the base plate, the tongue including a shoulder-forming portion 24 joined to and projecting approximately at right angles to the plane of the base plate, and the outer portion of the tongue converging forwardly toward the plane of the base plate and having a slightly rounded front end. The tongue 23, which extends from a long edge portion of the base plate, is considerably narrower than the length of the base plate, and the width of the tongue is slightly less than the width of the slots 19 in the shingle strips. The attached end of the tongue shoulder 24 has a junction with the base plate at a point set inward from the long upper edge of the base plate, thus forming a central notch 25 in the upper edge of the base plate, the retainer blank being slit, as seen in Fig. 6, to provide this relation. The base plate is thus provided with spaced upper edge portions 26 which project upwardly from the tongue shoulder at opposite sides of the tongue. The base plate is insertible between superposed shingle strips and is engageable with the underside of a shingle strip at opposite sides of a slot in the strip. Prongs or shoulders 27 are struck up from the base plate near opposite sides and are adapted to engage and become embedded in the bottom surface of the overlying shingle strip. The long lower edge of the base plate also forms a shoulder for this purpose. The corners of the base plate and of the tongue end are broken or rounded to facilitate insertion of the retainer.

As seen in Fig. 6, the shingle retainers can be formed from a sheet metal strip with very little scrap, successive T-shaped retainer blanks extending transversely across the strip in opposite directions with the tongue portion of each blank between the side edges of the base plates of adjacent blanks.

50 In applying the retainer to the roof, which may be either an existing roof or a new roof, the retainer is grasped by the tongue 23 and opposite ends of the retainer base plate 22 are slid upwardly under adjacent shingle tabs 20 at opposite sides of a slot 19, the tongue being moved upwardly in the slot to bring the tongue over the middle of the shingle tab at the upper end of the slot and to bring the tongue shoulder 24 against the lower edge of the latter shingle tab, as best seen in Figs. 2 and 3. The wide pronged base plate 22 engages and becomes

firmly embedded in the under surface of the overlying shingle strip or section, this surface being free of mineral surfacing. The resilient tongue 23 engages and presses downwardly over the mineral-surfaced weather face of the shingle tab in the superposed course, thus holding this tab in position against lifting by wind action. The tongue does not penetrate or tear the mineral-surfaced shingle tab, thus avoiding weakening and deterioration of this tab. The upper edges 26 of the base plate extend under the slotted shingle strip above the upper end of the slot, thus improving the engagement. However, the character and position of the base plate is such that the retainer is easily inserted, there being no interference with the shingle-securing nails 17. The wide base plate also resists swiveling and shifting of the retainer, and distributes the pressure on the overlying shingle. The narrow tongue, however, minimizes lodging of leaves and other debris.

The modified form of shingle retainer 31 shown in Fig. 7 is similar to that of Fig. 4 except that the sheet metal member 21 of Fig. 4 is partially or completely covered with a thin coating 28 of protective and adhesive material, such as asphalt. When the retainer is applied to the roofing this coating will adhere to the shingle surfaces, particularly after being warmed by solar or artificial heat.

It is also desirable to provide shingle retaining means at the edges of the roof. A roofing clip or retainer 41, shown in detail in Figs. 8 and 9 is suitable for this use. This clip or retainer comprises a piece of weather-resistant resilient sheet metal bent to form a substantially flat rectangular base plate 42 and a reversely bent spring tongue 43 spaced above the base plate, the tongue converging toward the plane of the base plate and having a shoulder portion 44 attached to the base plate. An upstanding flange 45 is formed along a long edge of the base plate to engage an edge of the roofing, and the tongue shoulder 44 projects from the middle portion of this flange and lies in the plane of the flange. The base plate is provided with struck-up prongs or shoulders 47 to engage and become embedded in the underside of a shingle for resisting withdrawal of the retainer. The retainer 41 embraces the edge portions of two superposed shingle strips, the base plate engaging the underside of the lower shingle strip and the roofing tongue 43 engaging and pressing down a tab 20 of the upper shingle strip, as seen in Fig. 8. The retainers 41 can be made from a multiple blank generally similar to that of Fig. 6.

In each form of the retainer the sheet metal member may be formed wholly of a rust-resistant metal or it may be formed of steel with a rust-resistant plating or coating.

The shingle retainers of the invention are also applicable to siding, and the term "roofing" as herein used includes siding.

What I claim as new and desire to secure by Letters Patent is:

1. A roofing retainer comprising a sheet metal member bent to form a base plate and an outwardly offset spring tongue projecting upwardly from the middle of the upper edge portion of said base plate, said base plate extending laterally at opposite sides of said tongue and having a notch in its upper edge at the junction of said tongue with said base plate, and said base plate projecting upwardly and downwardly from said junction, the downward projection of

said base plate from said junction being greater than the upward projection.

2. A roofing retainer comprising a sheet metal member bent to form a base plate and an outwardly offset spring tongue projecting upwardly from the middle of the upper edge portion of said base plate, the free end of said tongue extending higher than the upper edge of said base plate and adapted to press downwardly under spring action against the upper side of a roofing section, said base plate projecting downwardly below said tongue and the transverse dimension of said base plate being greater than the width of said tongue.
3. In combination, with roofing of the type having lapping upper and lower shingle strips each with laterally spaced shingle tabs separated by a slot with an open lower end and a closed upper end, the lower strip having a nailing area higher than but adjacent to the closed upper end of the slot in said strip, said upper strip overlying said lower strip and being upwardly offset on said lower strip, the closed upper end of the slot in the lower strip being adjacent to the central portion of the lower edge of a shingle tab of the upper strip, of a retainer comprising a base plate and an outwardly offset resilient tongue projecting upwardly from the upper edge portion of said base plate, said base plate being wider than said tongue and engaging the undersides of laterally adjacent shingle tabs of the lower strip at opposite sides of the slot in said strip, said resilient tongue extending outwardly in the slot of said lower shingle strip adjacent to the closed upper end of said slot, and said tongue having a free end portion overlying and pressing on the upper face of the adjacent shingle tab of the upper shingle strip.
4. In combination, with roofing of the type having lapping upper and lower shingle strips each with laterally spaced shingle tabs separated by a slot with an open lower end and a closed upper end, the lower strip having a nailing area higher than but adjacent to the closed upper end of the slot in said strip, said upper strip overlying said lower strip and being upwardly offset on said lower strip, the closed upper end of the slot in the lower strip being adjacent to the central portion of the lower edge of a shingle tab of the upper strip, of a retainer comprising a base plate and an outwardly offset resilient tongue projecting upwardly from the upper edge portion of said base plate, said base plate being wider than said tongue and engaging the undersides of laterally adjacent shingle tabs of the lower strip at opposite sides of the slot in said strip, the lower edge of said base plate forming a shoulder embedded in the undersides of said last-named shingle tabs, said resilient tongue extending outwardly in the slot of said lower shingle strip adjacent to the closed upper end of said slot, and said tongue having a free end portion overlying and pressing on the upper face of the adjacent shingle tab of the upper shingle strip.
